UNITED STATES PATENT OFFICE.

BERRY ANDERSON BROWN, OF FRANKLIN, OHIO, ASSIGNOR OF ONE-HALF
TO RUDOLPH J. MEISER, OF CINCINNATI, OHIO.

COLLAR-BUTTON.

SPECIFICATION forming part of Letters Patent No. 570,371, dated October 27, 1896.

Application filed February 24, 1896. Serial No. 580,418. (No model.)

To all whom it may concern:

Be it known that I, BERRY ANDERSON BROWN, a citizen of the United States, residing at Franklin, in the county of Warren and 5 State of Ohio, have invented certain new and useful Improvements in Collar-Buttons; and I do hereby declare the following to be a full, clear, and exact description of the invention, such as will enable others skilled in the art 10 to which it appertains to make and use the same.

This invention consists in an improved stud-button formed of two parts permanently attached together but connected by a screw, 15 and made so that they may be firmly and readily attached to an article of clothing for use, and in means by which the parts may be put together and then connected permanently together or removed, substantially as set 20 forth hereinafter and as illustrated in the accompanying drawings, in which—

Figure 1 shows the two parts of the button together ready for finishing. Fig. 2 shows the same completed. Fig. 3 shows a section of Fig. 1. Fig. 4 shows a section of Fig. 2.

This improved button is made with three button-plates A, B, and C, connected by a central and a hollow stud E F, fitted one into the other with screw-threads between them 30 on each.

The plate A forms a more or less rounded head, as illustrated. Plate B is connected to head A by a tubular or hollow stud F, made integral with parts A B, or in some cases of 35 separate pieces attached, if preferred, and having an internal screw-thread, as illustrated in Figs. 1, 2, 3, and 4.

The plate C bears a central stud E, with a screw-thread on it fitted to enter and connect 40 with that in stud F. This stud E is smaller below and enlarged above where it bears the screw-thread, and it is held in the hollow stud F by means of a stop, and the end of the tube of stud F is smaller than the head or enlarged 45 part of stud E and adapted to hold it in stud E.

Figs. 1 and 3 show the parts connected in the process of manufacture, with a projecting part below plate B, formed of suitable metal, and Figs. 2 and 4 show this part molded and compressed back onto the neck of stud E, so 50 as to engage and hold it in stud F, but free to turn therein to run the screw-threads together. This is done either by spinning or pressure. This prevents the separation of the two parts B and C, but holds them so they 55 can be screwed apart far enough to insert into a buttonhole, and then screwed together onto the fabric or garment, so as to tightly hold it between them, so that head A will project stud-like to enter another buttonhole for use. 60

I claim—

1. A button-stud formed of two pieces, one piece bearing a button-plate and a stem having an enlarged head fitting with a screw-thread in the hollow stem of the other piece 65 the other piece having a bottom plate and a head and a depending sleeve about the entrance to such hollow stem below the plate, adapted to be turned up after the insertion of the first piece, to prevent their separation 70 while leaving them free to move by means of the screw to bring the two plates together or apart, substantially as set forth.

2. A button-stud part formed of a hollow stem bearing a head and a plate, on its ends, 75 and a depending sleeve below the plate around the opening to such stem, and adapted to be spun or bent up to partly close such opening after the insertion of the stem of the other part to prevent its separation, substantially 80 as set forth.

In testimony whereof I affix my signature in presence of two witnesses.

BERRY ANDERSON BROWN.
